Patented Oct. 24, 1967

209,012

ANTI-FREEZE TESTER

Ronald E. McLin, Springfield, Ohio, assignor to Mid-Continent Manufacturing Co., Springfield, Ohio, a corporation of Ohio

Filed Dec. 2, 1966, Ser. No. 4,899

Term of patent 14 years

(Cl. D52—7)

FIGURE 1 is a front perspective view of the anti-freeze tester incorporating my design;

FIGURE 2 is a rear perspective view of the anti-freeze tester; and

FIGURE 3 is a bottom plan of the anti-freeze tester incorporating my design.

The essential features of the design reside in the full line portions of the drawing.

I claim:

The ornamental design for an anti-freeze tester, as shown and described
